BEET PICKER ATTACHMENT

Joseph Bratun, Pueblo, Colo.

Application March 21, 1950; Serial No. 150,999

7 Claims. (Cl. 209—109)

1

This invention relates to new and useful improvements in beet pickers, and more particularly pertains to means for selectively placing beets in a receiving bin or hopper free from dirt and other debris.

The primary object of this invention is to selectively place beets in a storage hopper without the same being accompanied by leaves, dirt and other debris that is commonly associated with the same upon being freshly removed from the soil and the tops removed therefrom.

Another important object of this invention is to provide an attachment capable of realizing the foregoing object with a minimum of injury to the beets.

Another object of this invention is to provide an attachment of this character which is automatically adjustable to handle beets of various uniform sizes, as well as lots of the same where-in there is wide variation in the individual sizes of the beets.

Still another important object of this invention is to provide suitable drive means connecting the axle of the wheel support to the operative part of the present invention which will permit the same the automatic adjustment of the preceding paragraph, yet which will be absolutely positive in function.

Still another important object of the present invention is to provide a device of this character which will be inexpensive in construction, reliable in operation, and highly efficient for the purposes intended.

The meritorious feature of the present invention resides in the means provided for automatic vertical adjustment of the drum with respect to the conveyor belt as well as to permit the same to oscillate to a limited extent about an axis parallel to the conveyor belt.

Still another important feature of the present invention resides in the positive drive means connecting the axle of the wheel support with the drum, which means do not interfere with the automatic function of the movement of the drum with respect to the conveyor belt.

A final important feature to be specifically enumerated herein resides in the inverted V-shaped trough, whereby the necessity of any further mechanical conveyor is obviated.

These, together with various ancillary objects and features of the invention, which will later become apparent as the following description proceeds, are realized by the present invention, one embodiment of which has been illustrated by way of example only in the accompanying drawings, wherein:

2

Figure 1 is a top plan view of the present invention;

Figure 2 is a side elevational view of the present invention, showing the same in operation;

Figure 3 is a front elevational view of the present invention;

Figure 4 is a vertical longitudinal sectional detail view of the present invention being taken substantially upon the plane of the section line

10 4—4 of Figure 3;

Figure 5 is a perspective detail view of the inverted V-shaped trough and the means provided for removing beets from the drum; and

Figure 6 is a perspective view of the U-shaped member that swivelly supports the drum.

Reference is now made more specifically to the accompanying drawings, wherein like numerals designate similar parts throughout the various views, and in which: The numeral 10 designates generally a beet receiving bin or hopper which is supported upon an axle 12 which carries at its opposite ends ground-contacting wheels 14, the wheel support or cart formed from the bin 10 and the axle and wheels 12 and 14 is provided with a draught tongue 16 having a clevis 18 at its forward end for attachment to a suitable towing vehicle, not shown.

A pair of spaced longitudinally extending plates 20 are secured to the forward and rear ends of the hopper 10 by bolts 22 and 24 respectively, the plates 20 being spaced inwardly from the side edges of the hopper 10. Journalled between opposite ends of the plates 20 are conveyor rollers 26 and 28 about which is entrained a conveyor belt 30, the conveyor roller 28 being provided with a sprocket 32 whereby the roller 28, the belt 30 and the roller 26 may be actuated. It will be readily appreciated that the sprocket 32 may be suitably driven by a flexible drive connected to a ground wheel if desired, however, since the present invention does not reside in the means by which the conveyor 30 is driven, it has not been deemed necessary to illustrate such driving means.

Permanently connected to an upstanding strap 34 carried at the forward end of the hopper 10 is a substantially U-shaped member best shown in Figure 6. The U-shaped member comprises a pair of legs pivotally connected to a tubular web member 38 by means of a pivot bolt 40 connecting the legs 36 and extending through the tubular web member 38. The web member 38 is in turn provided with a transverse extension 42 extending from intermediate the ends thereof, which extension 42 is provided with a stop collar 44 and is externally threaded adjacent its outer

end, whereby the U-shaped member is pivotally connected to the strap 34 by means of nut 46. It will thus be seen, by means of the pivot bolt 48 and the pivotal connection of the extension 42 with the strap 34 that the U-shaped member is swivelly connected to the forward end of the hopper 10.

As best shown in Figure 2, the U-shaped member extends rearwardly from the strap 34, and that the legs 36 are bent upwardly intermediate their ends as at 48, and have a drum 50 journaled between the outer ends thereof. The drum 50 is disposed above the conveyor belt 30 and is itself provided with a plurality of rows of pointed projections or teeth 52. It should be noted that the teeth 52 are arranged in axially spaced rows, and that the teeth themselves extend radially from the drum 50 in circumferentially spaced relation.

As best shown in Figures 1 and 5, an inverted V-shaped trough 54 is provided which straddles the legs 36, being secured thereto in any suitable manner as by welding or the like and by braces 58. A plurality of stripper rods 58 which are substantially parallel extend from the edge of the trough 54 immediately adjacent the drum 50 and extend between the spaced rows of teeth 52, the arrangement being such that the rods 58 terminate in close proximity to the circumference of the drum 52 and are substantially tangential thereto, so that during clockwise rotation of the drum 50 as shown in Figure 2, the rods or fingers 58 will remove objects that are impaled upon the teeth 52 therefrom and constitute a guide therefor into the trough 54 so as to slide to either side of the conveyor belt 30 and into the hopper 10. It will be noted that the trough 54 is greater in transverse extent than the conveyor belt 30 so as to insure the passage of objects directly from the trough 54 into the hopper 10.

As thus far described, it will be readily apparent that during travel to the left of the upper flight of the conveyor belt 30 as shown in Figure 2, and clockwise rotation of the drum 50, that beets which are received from the elevator conveyor 60 together with any refuse will pass under the drum 50, and that the teeth 52 will selectively impale the beets and carry the same into engagement with the rods 58 for their eventual deposit within the hopper 10. Due to the U-shaped member being swivelly connected to the hopper 10 it will be readily appreciated that the drum 50 may rise straight upward to conform to the size of the beets passing thereunder, and that the drum 50 is also capable of sidewise tilting to compensate for variations in the size of beets passing thereunder in any particular instance. While a sidewise tilting movement of the drum 50 is of great value, it has been found in practice that better performance may be obtained from the equipment if the tilting movement is limited, accordingly, vertical standards 62 extend upwardly from the plates 20 on opposite sides of the U-shaped member to limit this movement.

Means are provided to positively rotate the drum 50 during advance of the wheel support irrespective of the swiveling movement of the U-shaped member and the drum 50 carried thereby. These means include an upstanding support bracket 64 secured to one side of the hopper 10 and which carries at its upper end a transverse shaft 66. The transverse shaft 66 is operatively connected to the axle 68 of the drum 50 by means of universal couplings 70 between which an extensible coupling 72 is interposed. The extensible

coupling 72 may conveniently take the form of a non-circular shaft 74 slidably retained in a complementary non-circular socket member 76. It will be evident from the foregoing that upon rotation of the shaft 66 that the axle 68 will be positively driven thereby irrespective of the position of the drum 50.

The axle 12 projects laterally beyond one of the wheels 14 and is provided with a tubular housing 78 secured thereon by a nut 80, the member 78 being fixedly secured to the wheel 14 to rotate therewith and is provided with a driving sprocket 82, which driving sprocket 82 in conjunction with a driven sprocket 84 on the outer end of the shaft 66 serves to rotate the shaft 66 upon rotation of the ground wheels 14. In order to insure proper tension in the drive chain 86 entrained over the pulleys 82 and 84, an arm 88 is pivoted at 90 to the support bracket 64, which arm 88 carries at its outer end a chain tensioning sprocket 92, a spring 94 being provided to urge the sprocket 92 into engagement with the drive chain 86.

In the preferred construction means is provided to prevent reverse rotation of the drum 50, which means takes form in the present embodiment of a uni-directional clutch connected between the sprocket 84 and the shaft 66, so that upon rearward movement of the hopper 10 the drum 50 will not also rotate in reverse, it being apparent upon forward advance of the hopper 10 that the drum 50 will rotate in the desired direction for the proper operation of the drum 50 and the fingers 58.

It should be pointed out that in themselves the hopper or bin 10, the axle 12, the wheels 14, and the conveyors 30 and 60 do not constitute the subject matter of this invention, since they may conveniently take the form of apparatus manufactured for the International Harvester Co. as illustrated in the drawings.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. For use with a beet picker of the type having a receiving hopper provided with a wheeled support and an endless conveyor above the hopper, an attachment for selectively removing beets from the conveyor and depositing the same in the hopper comprising a substantially U-shaped member having a pair of legs connected by a web, means for swivelly connecting the web to the hopper, a drum journaled between the outer ends of the legs having a plurality of rows of radially extending and circumferentially spaced pointed projections, each of said rows of projections being axially spaced, an inverted V-shaped trough carried by said legs and adapted to straddle the conveyor belt for depositing beets into the hopper, a plurality of upwardly extending rods carried by the trough each of which extends into closely spaced relation with the periphery of the drum and into the spaces between the rows of projections.

2. The combination of claim 1 including means

for limiting movement of the drum about an axis substantially parallel to the legs.

3. Means for selectively removing beets from a conveyor comprising a substantially U-shaped member having legs pivotally joined by a web for vertical swinging movement thereabout, means for swivelly mounting the web to a support with the web transverse to the path of travel of a conveyor, a drum journaled between the outer ends of the legs, a plurality of axially spaced rows of radially extending and circumferentially spaced projections on the drum for empaling beets, an inverted V-shaped trough attached to the legs of the member and adapted to straddle the conveyor, and means carried by the trough responsive to rotation of the drum to remove empaled beets from the projections and also to deposit the same in the trough, and means for limiting swivelling movement of the member about an axis substantially parallel to the pair of legs.

4. In a beet picker, a receiving hopper supported by an axle and ground engaging by an axle and ground engaging wheels, an endless conveyor carried by the hopper and carried thereabove, a substantially U-shaped member having a pair of legs connected by a web, means swivelly connecting the web to the hopper with the web transversely disposed with respect to the conveyor, a drum journaled between the outer ends of the legs, and disposed above the conveyor, said drum having a plurality of axially spaced rows of radially extending and circumferentially spaced pointed teeth, an inverted V-shaped trough straddling the conveyor, a plurality of rods extending from the edge of the trough adjacent the drum which rods extend between the rows of teeth and terminate in close proximity to the drum, means for limiting swivelling movement of the drum about an axis parallel to the conveyor, and means operatively connecting the axle and the drum for rotating the drum.

5. In a beet picker, a receiving hopper supported by an axle and ground engaging by an axle and ground engaging wheels, an endless conveyor carried by the hopper and carried thereabove, a substantially U-shaped member having a pair of legs connected by a web, means swivelly

connecting the web to the hopper with the web transversely disposed with respect to the conveyor, a drum journaled between the outer ends of the legs, and disposed above the conveyor, said drum having a plurality of axially spaced rows of radially extending and circumferentially spaced pointed teeth, an inverted V-shaped trough straddling the conveyor, a plurality of rods extending from the edge of the trough adjacent the drum which rods extend between the rows of teeth and terminate in close proximity to the drum, means for limiting swivelling movement of the drum about an axis parallel to the conveyor, and means operatively connecting the axle and the drum for rotating the drum comprising a transverse shaft carried by the hopper, flexible drive means connecting the axle and the shaft, and means including a pair of universal joints with an extensible coupling therebetween connecting the shaft and the drum to permit swivelling movement of the drum.

6. The combination of claim 5 wherein said legs are pivotally secured to said web to permit vertical swinging of said legs.

7. The combination of claim 5 wherein said legs are upwardly bent at their outer ends to space said drum from said conveyor, the remaining portions of said legs serving as a beet guide means for said conveyor.

JOSEPH BRATUN.
